(57) CLAIM

The ornamental design for a “cosmetic package,” as shown and described.

DESCRIPTION

FIG. 1 illustrates a front view of a cosmetic package showing our new design; a rear view, a left side view and a right side view of the cosmetic package being same as the front view; FIG. 2 is a top view of the cosmetic package of FIG. 1; FIG. 3 is a bottom view of the cosmetic package of FIG. 1; FIG. 4 is an enlarged perspective view of the cosmetic package of FIG. 1 showing the claimed part and its surroundings; FIG. 5 is a partially exploded front view of the cosmetic package of FIG. 1 with an upper applicator removed; FIG. 6 is a front view of the cosmetic package of FIG. 5 without the upper applicator; a rear view, a left side view and a right side view of the cosmetic package of FIG. 6 being same as the front view of the cosmetic package of FIG. 6; FIG. 7 is a top view of the cosmetic package of FIG. 6; FIG. 8 is a bottom view of the cosmetic package of FIG. 6; and, FIG. 9 is an enlarged partial perspective view of the cosmetic package of FIG. 6 showing the claimed part and its surroundings. The broken lines shown in the drawings are included to show unclaimed environment only and form no part of the claimed design.
